Primary Examiner — Randall Gholson(74) *Attorney, Agent, or Firm* — Philip H. Burrus, IV(57) **CLAIM**

The ornamental design for a safety garment, as shown and described.

DESCRIPTION

FIG. 1 is a perspective view of one example of a safety garment, illustrating our new design;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof; and

FIG. 7 is a bottom plan view thereof;

FIG. 8 is a perspective view of another example of a safety garment, illustrating our new design;

FIG. 9 is a front elevation view thereof;

FIG. 10 is a right side elevation view thereof;

FIG. 11 is a rear elevation view thereof;

FIG. 12 is a left side elevation view thereof;

FIG. 13 is a top plan view thereof; and,

FIG. 14 is a bottom plan view thereof.

The dashed lines are included for the purpose of illustrating portions of the safety garment that form no part of the claimed design.

1 Claim, 8 Drawing Sheets(56)
